(57) **CLAIM**

The ornamental design for a teething toy, as shown and described.

DESCRIPTION

The patent or application file contains at least one photograph executed in color. Copies of this patent or patent application publication with color photographs will be provided by the Office upon request and payment of the necessary fee.

FIG. 1 is a top plan view of a teething toy showing my new design.

FIG. 2 is a right side elevational view thereof.

FIG. 3 is a front elevational view thereof.

FIG. 4 is a left side elevational view thereof.

FIG. 5 is a rear elevational view thereof.

FIG. 6 is a bottom plan view thereof.

FIG. 7 is a front, left side perspective view thereof; and, FIG. 8 is a front, right side perspective view thereof.

The functional indicia depicted on the back of the character's left leg in FIGS. 4 and 5 consists of the required European Conformity designation (i.e., “CE”), the manufacturer identification (i.e., “TOT”) and the product identification number (i.e., “15001”).
